US00D332084S

United States Patent [19]

Hollander et al.

[11] Patent Number: Des. 332,084

[45] Date of Patent: ** Dec. 29, 1992

[54] **ELECTRICAL CONNECTOR FOR
TEMPERATURE MEASURING EQUIPMENT**

[75] Inventors: Milton B. Hollander, Stamford; David R. Jacobs, Norwalk, both of Conn.

[73] Assignee: Omega Engineering, Inc., Stamford, Conn.

[**] Term: 14 Years

[21] Appl. No.: 763,770

[22] Filed: Sep. 23, 1991

[52] U.S. Cl. D13/133

[58] Field of Search D13/133, 137, 138; 439/169, 219, 482, 502, 600, 620, 638, 692, 809, 912

[57] **CLAIM**

The ornamental design for a electrical connector for temperature measuring equipment, as shown and described.

DESCRIPTION

FIG. 1 is a front elevational view of an electrical connector for temperature measuring equipment showing our new design. The broken line showing of the plug prongs is included for the purpose of illustrating environmental elements only and forms no part of the claimed design;

FIG. 2 is a right side elevational view thereof, the left side elevational view thereof being a mirror image;

FIG. 3 is a top plan view thereof;

FIG. 4 is a rear elevational view thereof; and,

FIG. 5 is a bottom plan view thereof.

FIG. 1

FIG. 2

FIG. 3

FIG. 4

FIG. 5
